(57) **CLAIM**

The ornamental design for a wheel for motor vehicle, as shown and described.

DESCRIPTION

FIG. 1 is a perspective view of a wheel for motor vehicle; FIG. 2 is a side view thereof; and,

FIG. 3 is a front view thereof.

In the drawings the broken lines depict portions of the wheel that form no part of the claimed design.

1 Claim, 3 Drawing Sheets

FIG. 1

FIG. 2

FIG. 3
